WILLIAM E. WATKINS, OF NEW YORK, N. Y., ASSIGNOR TO COPPER PLATE SHEET & TUBE COMPANY, OF NEW YORK, N. Y., A CORPORATION OF NEW JERSEY

CONVEYER FOR METAL SHEETS

Application filed December 27, 1929. Serial No. 418,826.

This invention relates to conveyers, and more particularly to a conveyer particularly adapted for transporting arched metal sheets through an annealing furnace. In my prior application, Serial No. 116,486, filed June 16, 1926, I have disclosed and claimed a process of annealing in which the sheets are arched transversely and then conveyed singly through an annealing furnace while in arched condition. While passing through the furnace the side edges of the sheet rest on transverse arms of a conveyer and the sheets are held in place by lugs or projections on the ends of these arms. In practicing the process of my prior application I have found that the sheets may be unevenly heated and when this occurs they tend to sag throughout a portion of the arch which sagging will displace the edge of the sheet from its position on the conveyer. In the present invention this difficulty is overcome by placing auxiliary arms on the transverse arms of the conveyer which auxiliary arms extend upwardly toward the curved portion of the sheet. If the sheet tends to sag at either side of the center of the arch it is engaged by one of these arms and further sagging is prevented before the opposite edge of the sheet springs out of position on the conveyer arm. In the accompanying drawings I have shown one form of the invention. In this showing, Fig. 1 is a vertical, sectional view of an annealing furnace showing the conveyer in operation; Fig. 2 is a side elevation of one of the furnace sprockets showing the arrangement of the conveyer chain; and Fig. 3 is a transverse, sectional view of the conveyer showing one of the transverse arms in elevation. Referring to the drawings, the reference numeral 1 designates the furnace which is formed of suitable refractory material and is provided with a longitudinal chamber or passage 2 through which the arched sheets are carried by the conveyer. The conveyer is supported throughout its travel within the furnace upon tracks or rails 3. The main burner of the furnace is illustrated at 4 and air is supplied to the burner through a pipe 5 from a suitable blower. The hot combustion gases pass through openings 6 in the refractory arch 7 and then come in contact with the advancing sheets A carried by the conveyer in the chamber or passage 2. Suitable sprockets are arranged at opposite ends of the furnace, one of the sprockets being shown at 9 in Fig. 2 of the drawings. After passing over the sprocket 9 at the rear of the furnace the conveyer chain travels forwardly through a chamber or passage 10 beneath the furnace. The conveyer forming the subject matter of the present invention comprises a chain formed of parallel links 11 connected by rollers 12 which are suitably spaced from each other to engage the sprockets 8 of the sprocket wheel 9. The sheets are supported by transverse arms 13 mounted on the conveyer at suitable intervals as shown in Fig. 2 of the drawings. These transverse arms are provided with upturned ends 14 which are adapted to engage the side edges of the sheet as shown in Figs. 1 and 3 of the drawings. Adjacent the center the lower surfaces of the arms are provided with bearing portions 15 adapted to engage the rails 3. Between the two bearing portions the arm is provided with a depending portion 16 having a pair of parallel arms 17. The lower faces of these arms are flattened or enlarged as at 18 and are adapted to receive ears or brackets 19 which are in turn secured to the links 11 of the conveyer chain. The construction heretofore described is disclosed in my copending application. In the present invention I provide two or more arms 20 extending upwardly from the transverse arm 13 which arms are adapted to engage the sheet if the sheet tends to sag and prevent the side edge thereof from springing out of position on the end of the transverse arm. The normal position of the sheet is represented in full lines in Fig. 3 of the drawings. The dotted line positions represent the positions of the sheet when uneven heating occurs or when the sheet is otherwise irregular. When the sheet sags on one side as indicated

by the dotted lines, the opposite side edge has a tendency to spring off the conveyer arm. The provision of the arms 20, however, limits the sag of the sheet as when a sheet sags it will contact with the end of the arm 20 as illustrated in Fig. 3 of the drawings. This will limit further downward movement of that side of the sheet and will prevent the other side edge from becoming displaced from its position on the conveyer arm.

I claim:

1. A conveyer for arched metal sheets comprising a conveyer chain, transverse arms secured to said chain and adapted to support the arched sheet, and arms carried by said transverse arms intermediate the ends of said transverse arms and extending upwardly a considerable distance therefrom to prevent sagging of said arched sheets.
2. A conveyer for arched metal sheets comprising a conveyer chain, a plurality of transverse arms carried by said chain and projecting on each side of said chain, and arms carried by said transverse arms and arranged on each side of the center thereof and spaced from the ends thereof, said arms extending upwardly a considerable distance from said transverse arms to prevent sagging of said arched sheets.
3. A conveyer for arched metal sheets comprising a conveyer chain, a transverse member adapted to be secured to said chain, said transverse member being provided with a depending central portion adapted to be secured to the links of the conveyer chain, and arms carried by said transverse member intermediate the ends of said transverse member and extending upwardly a considerable distance therefrom to prevent sagging of said arched sheets.
4. A conveyer for arched metal sheets comprising a conveyer chain, rails arranged on each side of said chain, a transverse member carried by said chain, said transverse member being provided with bearing surfaces adapted to ride on said rails, said transverse member being provided with a depending central portion adapted to be secured to the links of the conveyer chain, and arms carried by said transverse member intermediate the ends of said transverse member and extending upwardly a considerable distance therefrom to prevent sagging of said arched sheets.
5. A conveyer for arched metal sheets comprising a conveyer chain, rails arranged on each side of said chain, a transverse member carried by said chain, said transverse member being provided with bearing surfaces adapted to ride on said rails, said transverse member being provided with a depending central portion adapted to be secured to the links of the conveyer chain, means on each end of said transverse member for engaging the edge of an arched sheet to retain the

sheet on said conveyer, and arms carried by said transverse member intermediate the ends of said transverse member and extending upwardly a considerable distance therefrom to prevent sagging of said arched sheets.

6. A conveyer for arched metal sheets comprising a conveyer chain, a transverse member projecting on each side of said chain, means on each end of said transverse member for engaging the edge of an arched metal sheet to retain it in position on said conveyer, and arms carried by said transverse member intermediate the ends of said transverse member and extending upwardly a considerable distance therefrom to prevent sagging of said arched sheets.

In testimony whereof I affix my signature.

WILLIAM E. WATKINS.
